UNITED STATES PATENT OFFICE.

ARTHUR B. SHOBAR, OF LAMOILLE, NEVADA.

CHISEL-PROTECTOR.

1,258,481.

Specification of Letters Patent. Patented Mar. 5, 1918.

Application filed August 1, 1917. Serial No. 183,916.

To all whom it may concern:

Be it known that I, ARTHUR B. SHOBAR, a citizen of the United States, residing at Lamoille, in the county of Elko and State 5 of Nevada, have invented new and useful Improvements in Chisel-Protectors, of which the following is a specification.

This invention relates to special receptacles, and more especially to those for containing edge tools; and the object of the 10 same is to produce a protector for the cutting edges of highly tempered chisels.

It is well known that the careful workman protects his chisels when he puts them 15 in the tool box, so that their cutting edges will not become dulled and nicked by contact with the other tools or with any object therein. This protection is usually afforded by wrapping the outer end of the chisel in 20 cloth or the like, and some workmen slip over their chisels protectors in the shape of receptacles of various materials and sizes. The receptacle itself must be so bulky or 25 of such strength that it will stand accidental blows, and if means are not provided it will slip off the chisel in the tool box so that its usefulness comes to an end just at the time when it is necessary. It is hardly 30 worth while to give special shape to the blade of the chisel or other tool or provide the structure with special engaging devices for holding it in place, and yet it is desirable that some means be present to prevent its loss.

With these conditions in view I have 35 devised an improved protector which is of metal so that it has the necessary strength, is preferably of aluminum so that it has very little weight and cannot rust, and yet 40 which has peculiar formation whereby it is automatically held on the chisel and yet is not actually in contact with the cutting edge thereof.

Details are set forth in the following specification and reference is made to the drawings wherein—

Figure 1 is a perspective view of a chisel with this improved protector applied.

Fig. 2 is an end elevation of the structure, 50 showing the shape of the mouth of the opening therein.

Fig. 3 is a longitudinal section of the protector in place on the chisel.

In the drawings we will let the letter B 55 designate the blade of the chisel and C its

cutting end which as usual is beveled from the upper to the lower side of the blade and has a very fine cutting edge E at its extremity. My protector is preferably made of aluminum in box shape as shown, closed 60 along its two sides 1 and 2 and its lower end 3, and having its upper end or mouth open as seen at 4 in Fig. 2, and it may well be made of two pieces of aluminum connected along the two sides and lower end in 65 any suitable manner, or of one piece of double size bent upon itself in place of one such connection. In any case I prefer to make the lower side 5 flat because it underlies the flat lower face of the chisel blade, 70 and the upper side 6 I make originally flat and then give it a slight depression at its transverse center as best seen in Fig. 2—this depression running out at the lower end where the upper side is connected with the 75 lower side. Thereby is produced an inwardly sprung rib at the transverse center of the upper side of the mouth, which bears on the upper face of the blade with sufficient force to hold the entire protector in place. 80 The side edges 1 and 2 preferably converge upward as best seen in Fig. 2, and when the depressed top 6 is straightened out by inserting the chisel these sides swing outward a trifle as will be clear. Even if the blade 85 B is both thicker and narrower relatively than as shown in Fig. 1, it may be inserted in this protector because the top will arch upward to permit; and the convergence of the edges 1 and 2 permits the insertion of 90 a very thin blade, such as that of a putty knife which might be quite fully as wide as the lower side 5 and would extend out into an acute angle between this side and the edges—then it will be held in place as above 95 described. The front end of the top 6 is preferably beveled down to the front end of the bottom 5 at an acute angle sharper than that made by the bevel of the chisel at its extreme edge, so that the beveled face 100 on the top will extend beyond opposite sides of the beveled face on the chisel and prevent the cutting edge of the chisel from contacting with the closed end of the protector.

In using the device, before the workman 105 puts away his chisel he slides one of these protectors over its sharpened end, and the rib bears against it to hold it thereon so that it is safe to put the tool into a box with other metal tools. I can make the device any sizes, 110

and the workman should have one for each chisel. Even when well made, these protectors can be readily sold at a very low cost, and as they are practically indestructible they will not need replacing.

5 What is claimed as new, is—

1. The herein described sheet metal tool protector substantially of box shape comprising a flat bottom, edge members rising 10 integrally from the edges of said bottom and converging upward, a top connecting the inner edges of said edge members and having a depression at its transverse center, the lower end of the top being inclined down- 15 ward and connected with the lower end of the bottom at an angle sharper than that formed by the cutting edge of the ordinary

chisel, and the upper end of the protector being open, for the purpose set forth.

2. A protector for the cutting edge of cutting implements comprising a casing open 20 at one end and having an inclined top of concavo-convex shape in cross section, a wall at the opposite end of said casing inclining upwardly and outwardly from the bottom 25 to the top of said casing at a sharper angle and for a greater distance than the length of the beveled face adjacent the cutting edge on a cutting implement inserted in said casing, whereby the cutting edge on the cutting implement is prevented from contacting with the closed end of the casing.

In testimony whereof I affix my signature.

ARTHUR B. SHOBAR.
